His Attorney.

UNITED STATES PATENT OFFICE

OTTO ROSENLÖCHER, OF BERLIN, GERMANY, ASSIGNOR TO GENERAL ELECTRIC COMPANY, A CORPORATION OF NEW YORK

ELASTIC FLUID TURBINE AND THE LIKE

Application filed November 15, 1929, Serial No. 407,518, and in Germany December 8, 1928.

The present invention relates to rotating machines, such as elastic fluid turbines, ventilators, pumps, and the like, having rotating parts comprising buckets or blades through which the fluid current flows in an axial direction, and especially to means for separating from the fluid current heavier particles being carried along by it. In the case of elastic fluid turbines, the heavier particles may be in the form of drops of water which occur in the steam in the lower stages of the turbine; in the case of ventilators the heavier particles may be in the form of dust or similar material; and in the case of pumps the particles may be in the form of foreign material carried in the water or other liquid being pumped.

The object of my invention is to provide an improved construction and arrangement for separating such particles from the fluid current, and for a consideration of what I believe to be novel and my invention, attention is directed to the following specification and the claims appended thereto.

One application of my invention, and an important one, is in connection with elastic fluid turbines for separating out particles of water, and in the drawings and in the following specification I have especially illustrated and described my invention as applied to this use. It is to be understood, however, that the invention is not necessarily limited thereto.

In the drawings, Fig. 1 is a longitudinal sectional view of a portion of a turbine construction embodying my invention; Fig. 2 is a transverse sectional view of one of the buckets shown in Fig. 1; Fig. 3 is a transverse sectional view of a portion of a turbine structure taken on the line 3—3, Fig. 1, and Figs. 4 to 9 inclusive are detailed views of modifications.

Referring to the drawings, Figs. 1 to 3 inclusive, 1 indicates turbine buckets or blades carried by a bucket wheel 2, which in turn is mounted on a turbine shaft (not shown). In Figs. 1 and 2, 3 indicates the face of the bucket, and 4 indicates the back of the bucket. In advance of and beyond the bucket wheel are the usual nozzle diaphragms 5 and 6,

which convey the elastic fluid from one stage of the turbine to the next. 7 indicates the usual bucket cover held in place by the tenons 8. It will be understood that the turbine may comprise a number of stages. The one indicated may be one of the later stages of the turbine, for it is here that moisture in the elastic fluid is most frequently met with.

According to the embodiment of my invention illustrated in Figs. 1 to 3, for separating out the liquid particles, I provide one or more radially extending passages 9 which extend along the backs 4 of the buckets in proximity to the axial centers of the buckets and to permit of the outward flow of the liquid particles I provide passages 10 in the bucket cover which communicate with the radial passages 9. With this arrangement the liquid particles are caught in the passages 9 and are discharged radially outward through the passages 10 by means of centrifugal force. For removing the liquid particles, the surrounding casing is provided with an annular groove 11 which communicates with a chamber 12 which in turn may have connected to it a suitable drain pipe, (not shown). The annular groove 11 may be funnel-shaped in cross section, as shown in Fig. 1 and is provided with drain plates 11a in order the better to catch and convey away the liquid particles.

In connection with the operation of the arrangement, it will be understood that the particles to be separated out move at a slower speed than that of the medium passing through the buckets, and consequently the speed component of the particles to be separated out in the circumferential direction will be considerably less than the circumferential speed of the buckets. Consequently, the particles will be caught by the backs of the buckets and will strike the backs of the buckets at a high speed.

Since the particles to be separated out, in addition to being subjected to the axial acceleration due to the medium passing through the buckets, are exposed also to the centrifugal acceleration of the buckets, the upper ends of the backs of the buckets are

more especially attacked by these particles, which experience has shown to be the case.

The invention may be carried out to advantage in connection with hollow buckets, and in this case the backs of the buckets may be provided with openings communicating with the interior of the buckets. These openings may be either parallel or displaced with regard to each other. In Figs. 4 and 8 is shown an arrangement wherein the openings indicated at 13 are parallel with each other, and in Figs. 5 and 9 is illustrated an arrangement wherein the openings 14 are displaced relatively to each other. If desired, the openings may be in the form of slots arranged parallel to each other as indicated at 15 in Fig. 6, or arranged displaced relatively to each other as indicated at 16 in Fig. 7. In the modified arrangements, the bucket covers indicated at 17 will in each instance be provided with discharge openings 18.

In accordance with the provision of the patent statute, I have described the principle of operation of my invention, together with the apparatus which I now consider to represent the best embodiment thereof; but I desire to have it understood that the apparatus shown is only illustrative and that the invention may be carried out by other means.

What I claim as new and desire to secure by Letters Patent of the United States, is:

1. In an elastic fluid turbine, a rotor having buckets the backs of which are provided with radially extending passages, a bucket cover having openings communicating with said passages, and walls providing an annular chamber surrounding the bucket cover, and a passage in line with said openings and in communication with said chamber.

2. In an elastic fluid turbine, a rotor having buckets provided with radially extending passages, a bucket cover having openings communicating with said passages, an annular chamber surrounding the bucket cover, and a funnel-shaped passage in line with said openings and in communication with said chamber.

3. The combination with an elastic fluid turbine rotor having buckets the backs of which are provided with radially extending passages and a bucket cover having openings in communication with said passages, of a chamber surrounding the bucket cover, and communicating means between said chamber and the openings in the bucket cover.

In witness whereof, I have hereto set my hand this 31st day of October, 1929.

OTTO ROSENLÖCHER.
